(57) **CLAIM**

The ornamental design for packaging, as shown and described.

DESCRIPTION

The patent or application file contains at least one computer-generated image executed in color. Copies of this patent or patent application publication with color photograph(s) will be provided by the Office upon request and payment of the necessary fee.

FIG. 1 is a front top perspective view of packaging showing our new design;

FIG. 2 is a front elevation view thereof, the rear elevation view being a mirror image thereof;

FIG. 3 is a top plan view thereof;

FIG. 4 is a bottom plan view thereof;

FIG. 5 is a left side view thereof, the right side view being a mirror image thereof;

FIG. 6 is a front top left perspective view of the packaging shown in an alternate configuration, in which a lower portion of the packaging is separated from an upper portion, and positioned adjacent to the upper portion; and,

FIG. 7 is a front top left perspective view in the configuration of FIG. 7, showing bottles placed in the lower portion of the packaging when in use, the bottles not being part of the claimed design.

The portions shown in broken lines of equal length in FIGS. 6 and 7 form no part of the claimed design. The broken lines of unequal length in FIGS. 6 and 7 define the boundary of the claimed design, and form no part of the claimed design. The interior portion of the packaging that is not visible in FIGS. 6 and 7 forms no part of the claimed design.
